UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed May 3, 1923. Serial No. 636,462.

The present invention relates to power mechanism for starting hydrocarbon motors, and more particularly to that type of starter in which the motor thereof is connected to 5 the driving pinion by means of epicyclic reduction gearing.

The gearing in starters of this type and particularly in starters for airplane engines, is subjected to sharply changing torques and 10 loads. Thus when the engine is turned over from rest, a very heavy load and strain comes on the starter, and the load also varies throwing heavy shocks on the gearing, when the pistons of the engine are passing over the 15 compression points. The gearing must be constructed of greater strength than would be required if there were no shocks of the kind mentioned above.

It is the principal object of the present invention to provide means for eliminating 20 the effect of the excessive stresses and shocks to which the gearing is subjected, so that the life of the gearing will be prolonged and at the same time a reduction in the weight and 25 strength of the same may be obtained. According to the present invention this object is effected by mounting the reaction or stationary gear of the epicyclic train for rotation through a limited angle, and providing 30 yielding means for normally holding this gear in a definite position but permitting it to yield under excessive loads. Thus when the starting mechanism is subjected to the 35 variable loads mentioned above, the normally stationary gear of the train yields, thereby absorbing the shocks and excessive stresses to 40 which the gearing otherwise would be subjected, and eliminating to a very great extent the wear and injury which have occurred in the rigid gear trains heretofore employed.

Another object of the invention is to mount this yielding gear of the reducing train in such a manner that the gear together with 45 its yielding means may be interchanged with the rigid gear now employed and its mounting.

Other objects and features of novelty will be apparent from the following description 50 taken in connection with the drawings in which:

Figure 1 is a vertical longitudinal sectional view through a starter mechanism constructed in accordance with the present in-

vention, the electric motor being shown in 55 elevation, and the section being taken substantially on the line 1—1 of Figure 2.

Figure 2 is an end elevation of the mechanism showing the yielding device.

Referring to the drawings, the mechanism 60 illustrated is of a well known type particularly employed in connection with airplane engines. The casing of the electric motor which operates the starter mechanism is designated by the numeral 10. The epicyclic 65 gearing driven by the motor and transmitting the rotation thereof, at a greatly reduced rate to the driving pinion 60 is housed in a frame 11 which is secured to the casing 10 by means of bolts 12. The armature shaft 70 13 of the motor projects into the housing 11 and has keyed thereto a beveled pinion 14, which meshes with a large bevel gear 15. This large gear has a sleeve or hub secured to shaft 16 in any suitable manner as by being pinned thereto. Rigidly attached to gear 15, on each side thereof, is ring 17, the two rings being secured co-axially with the shaft and in spaced relation to gear 15 by means 75 of spacers 18 and bolts 19. The rings support a number of shafts 20 on each of which are journaled by roller bearings two integrally formed spur gears 21 and 22. The gears 21, which are of slightly greater diameter than the gears 22 mesh with an annular or internal gear 23 which is bolted 80 in an annular recess in the inner face of a head 24.

The smaller spur or planet gears 22 mesh 85 with an annular or internal gear carried by 90 a flange projecting from a nut member 43 which is journaled in a bearing 43^a in the housing 11. A screw member 44 of steep pitch is mounted in the nut member and is 95 adapted to be projected therefrom in a well known manner when the nut member is rotated by the gearing just described. This screw member 44 at its outer end carries rigidly therewith a spur pinion 60 which is 100 adapted to be thrown into mesh with the gear on the flywheel of the engine when the screw is projected. Mounted on the inner end of the screw 44 is a washer 45 which is adapted to seat against an annular face formed on a cover plate 46, when the screw 105 is retracted; and mounted on the screw next to the washer is a clutch disk 47 adapted to frictionally engage the nut member 43 when

the screw is projected by said nut, to clamp these parts together and thereby enable the pinion on the screw to drive the engine shaft.

The shaft 16, at one end, is mounted in a 5 roller bearing 61 housed in the hub of the cover plate 46 and at the other end is mounted in a ball bearing 62 carried by the head 24. A cover plate 48 screwed to the head 24 retains the outer race of the ball bearing in 10 position, and the inner race ring of this bearing is secured in position by a nut 49 on one side and a collar 50 on the other.

The mechanism thus far described is well known and except in so far as it is employed 15 in combination, specifically forms no part of the present invention.

The improvement constituting the present invention consists in the provision of means for taking up the shock due to varying 20 torques and loads, to which the gearing between the electric motor and the driving pinion is subjected. In the form of gearing illustrated herewith, this result is obtained by mounting the gear 23 for yielding rotative movement. Heretofore this gear has been rigid and unyielding. The means for 25 yieldingly supporting this gear comprises the head 24 to which the gear 23 is rigidly secured by means of the cap screws 23^a. This 30 head 24 consists of a disk-like web 25 and at its periphery has an inwardly extending cylindrical flange 26, being rotatively mounted within an annular member 27. The peripheral surface of the flange 26 and the corresponding bore of the annular member 27 35 are shouldered so as to prevent axial movement of the head 24 in an outward direction. The annular member 27 has an annular flange 28 fitted within an opening 28^a in the 40 housing 11, and also has a radial flange 29 which is clamped against the outer surface of the housing 11, by means such as the cap screws 27^a. This member 27 also includes an annular barrel portion 30.

Attached to the outer face of the head 24, by means such as the cap screws 31, is a plate 32 which has three equally spaced arms 33 projecting therefrom. From Figure 1 of the drawings it will be observed that the 45 outer face of disk 32 is approximately coplanar with the edge of the cylindrical flange 30, and so to provide for the passage of arms 33, this flange 30 is formed with recesses 34, providing shoulders 35 which are adapted to contact with the arms 33 and 50 limit the rotary movement of head 24 in one direction. The movement of the head 24 in the other direction is limited by stop plugs 36 formed integral with barrel 30.

Rotation of the head 24 and its disk 32 in one direction is yieldingly resisted by the 55 springs 39 interposed between a washer 41 carried by a rod 37 secured to the arms 33, on the one hand, and an abutment 42 bearing 65 against a lug 38 rigid with the annular

member 27 on the other hand. The tension of the springs 39 may be adjusted by the nuts 41^a threaded on the rods 37. As shown the abutments 42 have spherical seats 42^a in the lugs 38.

This construction is such that when the 70 gearing is subjected to an excessive torque or load, the annular gear 23 will yield rotatively to an extent depending upon the resiliency of the springs 39 and when the load 75 returns to the normal or uniform amount, the springs will act to return gear 23 to its usual position. In this manner the effect of the shocks and stress to which the gearing 80 has been subjected heretofore is eliminated.

The yielding gear together with its mounting forms a closure for one end of the housing. In the known constructions this gear has likewise been mounted so as to be carried by the closure for one end of the housing, but of course no yielding means were 85 provided. The construction according to the present invention is such that the closure for the housing carrying the gear and its yielding means may be interchanged with 90 the closure in the old constructions.

Although a specific embodiment of the invention has been described in detail it is to be understood that the invention is not thus limited but includes modifications and 95 changes which come within the scope of the appended claims.

Having thus described the invention what is claimed as new and desired to be secured by Letters Patent is:

1. A starter for hydrocarbon engines, comprising in combination, an electric motor, a pinion adapted to drive a gear on the engine, and an epicyclic reduction gearing between said motor and pinion including a yielding- 105 ly mounted normally stationary gear adapted to yield under excessive loads.

2. The combination with known engine 110 starter mechanism comprising an electric motor, a housing, a driving gear carried by said housing and adapted to mesh with a gear connected with an engine crank shaft, and reduction gearing in the housing connecting the motor and said driving gear; of a closure for one end of said housing interchangeable with present closures, a gear mounted on said closure for limited rotary movement and forming part of said reduction gearing, and means on said closure yieldingly resisting 115 rotation of said gear.

3. An electrically operated starter for hydrocarbon engines, comprising in combination, an electric motor having a casing, a housing bolted to said casing, a nut journaled in said housing, a screw in said nut having a gear on the outer end thereof adapted to be projected into engagement with a gear on the engine clutch means to lock said nut and screw together, and a reducing gearing 125 between said motor and nut comprising a 130

normally stationary reaction gear yielding-
ly mounted in said housing for limited ro-
tary movement.

4. A starter for hydrocarbon engines,
comprising in combination, an electric mo-
tor having a casing, a housing bolted to said
casing, a bevel pinion fixed to the armature
of said motor, a large bevel gear rotatably
mounted in said housing and meshing with
said pinion, a plurality of pairs of rigidly
connected planet gears carried by said large
bevel gear, an internal gear surrounding the
larger gears of said pairs and meshing
therewith, means for mounting said in-
ternal gear for rotary movements in said
housing comprising a cylindrical head to
the inner face of which said internal gear is
fixed, and a barrel member having a cylin-
drical portion fitting in an open side of said
housing and having a radial flange bolted
to said housing, said head being rotatably
mounted in said barrel member, stops on said
barrel member adapted to limit the angle
through which said head may rotate, springs
yieldingly holding said head in a normal po-
sition and adapted to yieldingly resist rota-
tion of said head under the reactive forces
exerted on said internal gear, a nut member
journaled in said housing and having an an-
nular flange formed with internal gear teeth
meshing with the smaller gears of said pairs,
and a screw operated by said nut having a
gear fixed to its outer end adapted to be
projected into engagement with a gear on the
engine.

5. A starter for hydrocarbon engines,
comprising in combination, an electric mo-
tor having a casing, a housing bolted to said
casing, a bevel pinion fixed to the armature
of said motor, a large bevel gear rotatably
mounted in said housing and meshing with
said pinion, a plurality of pairs of rigidly
connected planet gears carried by said large
bevel gear, said gears of each pair differing
in size, an internal gear surrounding the
larger gears of said pairs and meshing there-
with, means for mounting said internal gear
for rotary movements in said housing com-

prising a cylindrical head journaled in said
housing to the inner face of which said in-
ternal gear is secured, a plate secured con-
centric with said head on the outer face
thereof and having a plurality of arms pro-
jecting tangentially therefrom, rods pivoted
to the outer ends of said arms, apertured
lugs secured to said housing, said rods pass-
ing through said lugs, abutments secured to
the outer ends of said rods and to said lugs,
compression springs surrounding said rods
and bearing at their ends against said abut-
ments, a nut journaled in said housing and
having an annular flange formed with in-
ternal gear teeth meshing with the smaller
gears of said pairs, and a screw operated by
said nut having a gear on its outer end
adapted to be projected in engagement with
a gear connected to the engine.

6. A starter for hydrocarbon engines,
comprising in combination, an electric motor
having a casing, a housing bolted to said
casing, a bevel pinion fixed to the armature
of said motor, a large bevel gear rotatably
mounted in said housing and meshing with
said pinion, a plurality of pairs of rigidly
connected planet gears carried by said large
gear, said gears of each pair differing in
size, a normally stationary gear meshing
with the larger gears of said pairs, means for
mounting said normally stationary gear for
rotary movements in said housing comprising
a cylindrical head journaled in said
housing to the inner face of which said nor-
mally stationary gear is secured, an arm
secured to the outer face of said head and
a spring interposed between said housing and
arm, a nut journaled in said housing, a gear
connected to said nut and meshing with the
smaller gears of said pairs, and a screw
operated by said nut having a gear on its
outer end adapted to be projected into en-
gagement with a gear connected to the en-
gine shaft.

In testimony whereof I hereunto affix my
signature.

LIONEL M. WOOLSON.
